United States Patent Office

Des. 212,310

Patented Sept. 24, 1968

212,310

DESK CALCULATOR

Henry Dreyfuss, Pasadena, Calif., assignor to Sperry Rand Corporation, New York, N.Y., a corporation of Delaware

Filed July 21, 1967, Ser. No. 7,927

Term of patent 3½ years

(Cl. D64—11)

FIG. 1.

FIG. 2

FIG. 3.

FIG. 4.

FIG. 5.

FIG. 1 is a front perspective view of a desk calculator showing my new design;

FIG. 2 is another front perspective view thereof as it appears with the keyboard cover in closed position;

FIG. 3 is a top plan view of the desk calculator as it appears in FIG. 1;

FIG. 4 is a side view thereof; and

FIG. 5 is a rear view thereof.

I claim:

The ornamental design for a desk calculator, substantially as shown and described.
